CLAIM

The ornamental design for a pincer tongs for grasping, as showing and described.

DESCRIPTION

FIG. 1 is a front perspective view of the first embodiment of the pincer tongs for grasping showing our new design.

FIG. 2 is a front elevational view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front perspective view of the second embodiment of the pincer tongs for grasping.

FIG. 9 is a front elevational view thereof.

FIG. 10 is a rear view thereof.

FIG. 11 is a right side view thereof.

FIG. 12 is a left side view thereof.

FIG. 13 is a top view thereof.

FIG. 14 is a bottom view thereof.

FIG. 15 is a front perspective view of the third embodiment of the pincer tongs for grasping.

FIG. 16 is a front elevational view thereof.

FIG. 17 is a rear view thereof.

FIG. 18 is a right side view thereof.

FIG. 19 is a left side view thereof.

FIG. 20 is a top view thereof; and,

FIG. 21 is a bottom view thereof
